RETRACTABLE WINDOW ENCLOSURE

Robert Pitcoff, New York, N.Y., assignor to Epoch Products Corporation, New York, N.Y., a corporation of New York

Application June 16, 1954, Serial No. 437,045

5 Claims. (Cl. 160—269)

My invention relates to a retractable or roll-away window enclosure such as a screen or storm window.

In my copending application, Serial No. 293,926, filed June 17, 1952, issued November 6, 1956, as Patent No. 2,769,491, I disclose an enclosure consisting of a roll of screen or storm window webbing contained in a housing mounted at the top of a window and a rail on each side of the window casement for guiding and locking the edges of the web when unrolled. The present invention is similar in its broad aspects but is more specifically directed to a new guide rail and to a novel coil spring assembly in the core upon which the web is wound.

For a fuller understanding of the nature and objects of the invention, reference should be had to the following detailed description of one embodiment of the invention taken in connection with the accompanying drawings, in which:

Figure 1 is a perspective view, partially broken away, of a double-hung window having a retractable enclosure mounted inside the casing with a screen web fully unrolled;

Figure 2 is an enlarged view, partially broken away and partially in section, taken along line II—II of Figure 1;

Figure 3 is a fragmentary view taken along line III—III of Figure 2;

Figure 4 is a fragmentary view, partially in section, of one end of the web roll housing;

Figure 5 is a view taken along line V—V of Figure 4;

Figure 6 is an enlarged fragmentary view of a portion of Figure 5, and;

Figure 7 is an exploded view in perspective of the components shown in Figure 4.

Similar reference characters refer to similar parts throughout the several views of the drawings.

Referring now to Figure 1, a double-hung window 8 has disposed within its inside casing 9 a retractable window screen enclosure 10. The enclosure comprises a web 11 of screen wire spanning window 8 between a pair of side rails 12 and 13, and a housing 14 mounted at the top of the window casing on a pair of brackets 14a bolted to the window casing. The housing contains a core 15 to which one end of web 11 is fixed and is generally rectangular in cross-section, with three sides closed and the fourth (bottom) side open for passage of the web. The web is urged to a rolled position by a spring mechanism associated with the core, as described below. The free or travelling end of the web is provided with a stiffening bar 16 to which is attached a flexible looped takeup strip 17.

Side rails 12 and 13 are constructed similarly and have the same functions, so only side rail 12, shown in Figures 2 and 3, is described hereafter. Side rail 12 consists of a fixed angle bar 18 extending to the window sill from a point just below housing 14. The angle bar is mounted with one flange 19 against the upright of

2

window casing 9 and with its other flange 20 free and adjacent the window behind screen web 11 as the web is unrolled. A movable angle bar 21 is superimposed over angle bar 18 with its free flange 22 inwardly of flange 20 and parallel thereto. The other flange 23 of movable bar 21 is provided with a plurality (illustratively five) kidney-shaped slots 24 each similarly located with respect to flange 22 and forming a cam extending downwardly away from the window. Corresponding in position to each cam slot 24 is a circular hole 25 in flange 19 fitted with a hollow rivet 26 having rolled ends to hold angle bars 18 and 21 together loosely and to serve as a follower over which the cam slot may be moved. All holes 25 are aligned, and screws 27 fitting through rivets 26 fasten the assembly to window casing 9. The contour of cam slots 24 and their locations with respect to the center of gravity of movable angle bar 21 are such that bar 21 is free to move by gravity over rivets 26 downward away from the window, by the cooperative action of all cam slots 24, to the dotted line position shown in Figure 2. In so moving free flanges 20 and 22 become separated. Contrariwise, cam slots 24 permit angle bar 21 to be lifted and thereby shifted toward the window to move free flange 22 against free flange 20. This latter action is effected with minimum upward movement in using the arcuate cam slots 24 illustrated wherein the concavity is on the underside. In the alternate, straight slots slanted downwardly may be used satisfactorily where less pronounced lateral movement of angle bar 21 upon elevation is desired. Also, the linkages between the angle bars could be reversed by having pegs projecting from flange 23 through cam slots in flange 19, with collateral means for fastening angle bar 18 to the window casing, or the linkages could comprise bars each with one end rotatably connected to flange 23 and the other similarly connected to flange 19, with a suitable limit stop to retain the movable angle bar past dead center in its downmost position.

The top edges 29 and 30 of the free flanges 22 and 20 respectively are bent toward the window to accommodate web 11 as it is unrolled from core 15, while the lower end of movable angle bar 21 is capped with a rectangular plate 28 engageable by the end of stiffening bar 16.

The foregoing construction provides positive guiding and locking for the longitudinal edge of web 11 by allowing the edge to travel along the space between free flanges 20 and 22 of the angle bars. As the screen in unrolled angle bar 21 is in its normal or down position with the passage between flanges 20 and 22 correspondingly expanded. When the web is fully withdrawn and the end of stiffening bar 16 is slipped beneath plate 28 and the stiffening bar is released, rewind spring of core 15 draws angle bar 21 upwardly and urges the free flanges together due to the cam action described above. The opposite edge of web 11 is given the same treatment by side rail 13. Both edges are thereby firmly retained over substantially their entire lengths, and, indeed, any force against the body of the screen which might otherwise tend to pull the edges free is active to elevate stiffening bar 16 and force the movable angle bars into an even tighter grip on the edges.

The screen, or storm window web as the case may be, thus is operable in one continuous motion. To enclose the window, stiffening bar 16, which prevents the travelling end of web 11 from entering housing 14, need only be grasped with one hand and lowered to the window sill, then drawn toward the operator to hook the edges beneath the movable angle bars of the side rails, and released. The rewind spring action of core 15 completes the edge locking without additional effort on the

part of the operator, and takeup strip 17 seals the gap between the stiffening bar and the window sill. Now when the screen is to be retracted, one need only move stiffening bar 16 toward the window to free the edges from the movable angle bars and allow the angle bars to drop, and then release the stiffening bar for retraction of the web by core 15. Absence of manual latching mechanisms adds to the convenience, simplicity and economy of my window enclosure and eliminates a common source of malfunctioning.

As previously mentioned, core 15 urges web 11 to a rolled position by a spring mechanism, now to be described. A concentric bore 15a (Figure 4) in the left side of core 15 contains a coil spring 31 fastened at one end (not shown) to core 15 and at the other end to an axial cylindrical shaft 32 which is rotatable to increase the tension of spring 31. Shaft 32 has a flattened extremity and extends through a central hole in a cover plate 34 that is shaped to enclose the end of housing 14, and through a similar central hole in a lock plate 35 adapted to be inserted next to cover plate 34. Lock plate 35 has oblong slots 36 equidistant above and below its central hole and a flange 37 on its lower edge provided with a female button 38 to coincide with a male button 39 on flange 40 of bracket 14a for convenience of positioning during assembly.

Adapted to fit between lock plate 35 and bracket 14a is a triskelion spring tension retainer 41 having a rectangular hole 42 in its center slightly larger than the flattened extremity of shaft 32 and three arms 43 the length of the distance between either slot 36 and the central hole of lock plate 35. Each arm 43 has a tip 44 on the end extending counterclockwise and bent toward lock plate 35 as viewed in Figure 5, the tip being a little smaller than each slot 36. The final element of the mechanism is a round washer 45 with a centralized rectangular hole like hole 42 in retainer 41 but small enough for a tight fit over the end of shaft 32.

The right-hand side of the unit, though not illustrated, is relatively simple. It includes an axial cylindrical shaft extending from the end of core 15 and a cover plate for the housing similar to cover plate 34 with a central hole through which the shaft projects to suspend the core for rotation. The cover plate and the edge of the housing rest on the right-hand bracket 14a.

In assembling the spring mechanism, with core 15 supporting rolled web 11 within housing 14 and the housing removed from brackets 14a, plates 34 and 35 are slipped successively into the open end of housing 14 with shaft 32 fitting through the central hole of each, and then retainer 41 is inserted over the flattened extremity of shaft 32 and is turned clockwise as viewed in Figure 5 until the desired tension is wound into spring 31. At this point one of the tips 44 is eased into a slot 36 (Figure 6) to lock spring 31 against unwinding. Thereafter core 15 may be rotated in either direction without interference, while always urging web 11 to a wound position. Now after washer 45 is pressed over the end of shaft 32 the components are held together firmly and will not separate under normal handling. The housing may then be inserted over brackets 14a with the longitudinal edges of web 11 fed between free flanges of side rails 12 and 13, to complete the window enclosure. The enclosure's operation in conjunction with the side rails for locking the web when fully withdrawn is as described earlier.

In the claims and in the above description I refer to a "retractable window screen." By this expression I mean to include screening, flexible transparent material, and other materials suitable for a retractable window covering. Moreover, it is to be understood that housing 11 and side rails 12 and 13 may be used the year round by having a screen roll for the summer interchangeable with a clear plastic roll serving as a storm window in

the winter. Alternatively, housing 11 could be enlarged to contain both types of rolls, each with a stiffening bar on its travelling end and each movable separately within side rails 12 and 13, so that the appropriate covering to suit the weather is selectable conveniently without delay.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

15. 1. In a retractable window screen mountable at the top of a window casing and having spring means urging the screen to retracted position and a stiffening bar on the travelling end of the screen, the combination of a clamping bar mountable longitudinally along the side of the window casing on one side of an edge of the screen when extended, angular cam means on said clamping bar disposed off the center of gravity of said clamping bar in the direction away from said screen and guiding free movement of said clamping bar normally in a downward direction away from said screen but against said screen when said clamping bar is elevated, means for mounting said clamping bar to the window casing leaving free movement of said clamping bar along said cam means, stationary means on the other side of said unrolled edge of the screen against which the screen is clamped upon elevation of said clamping bar as guided by said cam means, and means at the base of said clamping bar engageable with said stiffening bar when the screen is extended, said engageable means, when engaged with said stiffening bar, thereby elevating said clamping bar and clamping said screen by the force of said spring means.

20. 2. In combination, a retractable window screen mountable at the top of a window casing, spring means urging the screen to retracted position, a stiffening bar on the travelling end of the screen and a locking mechanism along each longitudinal edge of the screen when extended, each locking mechanism comprising a clamping bar mountable longitudinally along the side of the window casing on one side of an edge of the screen when extended, angular cam means on said clamping bar disposed off the center of gravity of said clamping bar in the direction away from said screen and guiding free movement of said clamping bar normally in a downward direction away from said screen but against said screen when said clamping bar is elevated, means for mounting said clamping bar to the window casing leaving free movement of said clamping bar along said cam means, stationary means on the other side of said unrolled edge of the screen against which the screen is clamped upon elevation of said clamping bar as guided by said cam means, and means at the base of said clamping bar engageable with said stiffening bar when the screen is extended, said engageable means, when engaged with said stiffening bar, thereby elevating said clamping bar and clamping said screen by the force of said spring means.

25. 3. An edge-locking mechanism for a retractable window screen mounted at the top of a window casing and having spring means urging the screen to retracted position and a stiffening bar on the travelling end of the screen, said mechanism comprising in combination an angle bar having a free flange movable against the edge of an extended screen, and another flange with a plurality of cam slots slanting downwardly and away from said edge and disposed off the center of gravity of said angle bar in the direction away from said edge, cam follower means loosely mounting, through said cam slots, said angle bar to the side of a window casing, and means at the base of said angle bar engageable with said stiffening bar when the screen is extended.

4. The combination according to claim 3 in which the cam slots are arcuate with concavity on the underside.

5. An edge-locking mechanism for a retractable window screen mounted at the top of a window casing and having spring means urging the screen to retracted position and a stiffening bar on the travelling end of the screen, said mechanism comprising in combination a first angle bar having a free flange movable against the edge of an extended screen, and another flange with a plurality of cam slots slanting downwardly and away from said edge and disposed off the center of gravity of said first angle bar in the direction away from said edge, cam follower means loosely mounting, through said cam slots, said angle bar to the side of a window casing, a second angle bar positioned on said side with one flange parallel to and separated from the free flange of said first angle bar, thereby forming an expandable guide channel for one edge of said screen during extension, and means at the base of

said first angle bar engageable with said stiffening bar when the screen is extended, said engageable means, when engaged with said stiffening bar, thereby elevating said first angle bar and clamping said one edge between the two parallel flanges by the force of said spring means.
